Norbert Leopoldi, 4180 Marine Drive, Chicago, Ill.

Filed July 6, 1965, Ser. No. 86,032

Term of patent 14 years

(Cl. D86—10)

FIGURE 1 is a perspective view of a fingernail file showing my new design;

FIGURE 2 is a top plan view of the fingernail file;

FIGURE 3 is a bottom plan view of the fingernail file;

FIGURES 4 and 5 are edge views thereof taken in the direction of the lines 4—4 and 5—5 of FIGURE 2; and

FIGURE 6 is a cross-sectional view through the fingernail file, taken substantially along line 6—6 of FIGURE 2.

I claim:

The ornamental design for a fingernail file, substantially as shown.
